UNITED STATES PATENT OFFICE.

GEORGE C. BEIDLER, OF ROCHESTER, NEW YORK.

COPY-HOLDER.

1,175,221.

Specification of Letters Patent. Patented Mar. 14, 1916.

Application filed May 13, 1909. Serial No. 495,712.

To all whom it may concern:

Be it known that I, GEORGE C. BEIDLER, a citizen of the United States of America, residing at Rochester, in the county of Monroe and State of New York, have invented certain new and useful Improvements in Copy-Holders, of which the following is a specification.

This invention relates to photography and particularly to a class thereunder known as camera supports—copy holding.

An object of this invention is to provide a copy holder to be utilized in connection with a camera and in connection with a base or support made adjustable in much the same manner as my copy holder disclosed in my Patent Number 793,978, dated July 4, 1905, wherein the copy holder is hinged with relation to the said base.

The present invention consists in part of a copy holder which may be substituted for the copy holder disclosed in the patent above mentioned and which may be employed in connection with a base of similar construction. In fact the copy holder of the patent and the one forming the subject matter of this application are interchangeable on the base.

The invention has for its object to provide a copy holder having clamps whereby one or a plurality of leaves of a book or copy may be held substantially at right angles to the remainder of the book or copy and as said invention is now employed, the matter to be photographed is clamped to a vertically disposed portion of a holder whereas other matter such as leaves of a book or copy lie horizontally and are clamped on an extension of the support.

This invention has been found useful in reproducing copies on a large scale as for instance where the contents of a page or record is to be photographed substantially the size of the original or when but one page is to be exposed. The copy holder patented heretofore as identified herein, provides for exposing both leaves of a book or copy at a time.

This invention has for its further object the provision of clamps which are slideable and adjustable with relation to the copy holder in order that the holder may be adapted to hold copy of different dimensions and the clamps are further movable to engage copy varying in thickness since means are provided to permit reciprocal movement

of the clamps with relation to the faces of the support and to oscillate on planes parallel with the faces of said support, thus enabling the operator to adjust the clamps for engaging copy in order to flatten the exposed surface of the said copy.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1, illustrates a side elevation of a base and a copy holder embodying the invention; Fig. 2, illustrates an elevation of the front thereof, the base being shown in section; Fig. 3, illustrates an elevation of the rear of the device shown in Fig. 1; Fig. 4, illustrates a top plan of the said device with the base broken away; Fig. 5, illustrates a modified base having means for adjusting the copy holder with relation to the base; Fig. 6, illustrates a detail view of one of the clamps; and Fig. 7, illustrates a sectional view of one of the sliding sleeves applied to a slot of the copy support.

In these drawings 1, denotes a base which preferably comprises telescopic sections as in my former patent heretofore referred to, and the said base has a standard 2, to which a holder is connected by the hinges 3, and on which said holder is supported.

As shown in the drawing, the holder comprises two portions standing at right angles to each other, one portion to be hereinafter termed the bottom 4, and the other portion to be hereinafter termed the back 5. The bottom and back are connected by braces 6, for the purpose of increasing the rigidity of the structure and the said bottom and back are provided with clamps for holding copy thereon. The back is provided preferably with two slots 7 and 8, in which the clamping members are adjustable and the bottom is likewise provided with slots to receive the clamps. The clamps are of the same construction and therefore a description of one of the clamps will suffice for the purpose of disclosing the structure and operation of all of the clamps which coact with the copy holder. Each clamp has a sleeve 9, slideable in a slot and one end of the sleeve is pro-

vided with a flange 10, which engages one surface of the copy holder, whereas the opposite end of the said sleeve is threaded to receive the ring nut 11, which serves to hold the sleeve in its slot. A rod 12, is slideable in the sleeve and has one end screw threaded to receive the nut 13.

The sleeve 9, is threaded to receive a nut 14, and a spring 15, is applied to the rod 12, interposed between the nuts 13 and 14. The spring 15, holds the rod normally projected and the inner end of each rod which extends through the sleeve 9, is provided with a collar 16, adjustably held on the said rod by a binding screw 17. The collar has a lug 18, which is designed to engage copy such as a book or the like. The rod is rotatable in the sleeve and is slideable longitudinally therein, hence pressure on the outer end of the rod will force the lug 18, from the face of the copy holder until it has passed the plane of the copy applied to the holder after which rotation of the rod will cause the lug to overlie the copy. When the rod is released, the spring will exert pressure to hold the lug in engagement with the copy.

Mounted on the rod 12, is a plurality of fingers 19, which are rotatable with relation to the rod in order that the angle of the fingers with relation to each other and with relation to the lug 18, may be effected to cause the fingers to press the copy at the desired points. If the copy has a tendency to buckle or roll, the fingers can be properly adjusted to overcome the tendency so that the copy may be held flat with relation to the surface of the holder. The fingers are held on the rod and in contact with each other by means of the thumb nut 20, which is threaded on the inner end of the rod, it being apparent from an inspection of Fig. 6, that one of the fingers is in engagement with the collar 16, whereas the other finger is engaged by the thumb nut, but the parts are held in assembled relation, as stated, through the medium of the said thumb nut.

The back and bottom of the holder are each preferably provided with two rods and the clamping rods associated therewith.

Fig. 4, illustrates the manner of utilizing the copy holder for holding a book in which it will be seen that the back is open and one of the backs of the book lies in contact with the back of the copy holder whereas the other back of the book is lying on the bottom of the said copy holder, both portions of the book being held in place through the medium of the clamps heretofore described.

In Fig. 5, I show a modified construction, in that the standard 21, is provided with a bracket 22, which is slotted as at 23, to receive the bolts 24, which bolts are slideable in the slotted portion of the bracket in order that the holder 25, may be adjusted longitudinally of the bracket. In some instances,

this construction might be utilized for the purpose of changing the position of the copy holder with relation to the camera for focusing the instrument. The construction shown in Fig. 5, could be used independently of a base having telescopic sections or it might be used in conjunction therewith. It is to be understood that clamps similar to those heretofore disclosed may be used in connection with the copy holder in Fig. 5, or they may be omitted.

I claim—

1. In a copy holder, a copy holding member having slots therein, members movable in the slots, copy engaging devices, means in the members in the slots for carrying the copy engaging members, and means bearing against the member movable in the slot and engaging a portion of the means for carrying the copy engaging devices for holding the said copy engaging devices in contact with the copy.

2. In a copy holder, a member having slots therein, members movable in the slots and having apertures at right angles to the plane of the copy holding member, copy engaging devices, means in the members in the slots and slideable in the apertures thereof for carrying the copy engaging devices, and means for moving the slideable device in the members movable in the slots.

3. In a copy holder, a copy holding member, the said copy holder having slots, sleeves slideable in the slots, members slideable in the sleeves, copy engaging members on the said members, and means whereby the said copy engaging members are pressed into engagement with copy on the copy holding member.

4. In a copy holder, a copy holding member having slots, sleeves slideable in the slots, rods slideable in the sleeves, a collar on each rod having a lug, fingers rotatable on each rod, means for clamping the fingers and the collar in operative relation, and means for compressing the fingers into engagement with copy on the copy holding member.

5. A copy holding member having slots therein, sleeves adjustable in the slots, rods slideable in the sleeves, a collar on each rod having a lug, fingers rotatable on each rod, means for clamping the fingers and collar in operative relation, and means for compressing the fingers into engagement with copy on the copy holding member.

6. In a copy holder, a base, a standard, a copy support mounted on the standard, said support having slots therein, sleeves adjustable in the slots, a rod slideable in each sleeve, a collar on each rod having a lug, fingers rotatable on each rod, means for clamping the fingers and sleeve in operative relation, and means for pressing the copy engaging members into engagement with said copy.

7. In a copy holder, a base, a standard, a bracket on the standard, a copy support adjustable with relation to the bracket, said support having slots therein, sleeves adjustable in the slots, a rod slidable in each sleeve, a collar on each rod having a lug, fingers rotatable on each rod, means for clamping the fingers and sleeve in operative relation, and means for pressing the copy engaging members into engagement with said copy.

8. In a copy holder, a support for the copy, said support having slots, sleeves adjustable in the slots, each of said sleeves having a flange and a nut whereby the sleeve is guided in the slot, a rod slidable in the sleeve, a spring encircling the rod, and nuts for confining the spring and clamps on the rod.

9. In a copy holder, a support having slots, a sleeve in each slot, a nut threaded on the sleeve, a rod slidable in the sleeve, a spring encircling the rod and having its end bearing against the nut, a nut threaded on the outer end of the rod for confining the outer end of the spring, a collar on the rod near its inner end, fingers on the rod, and a nut on the inner end of the rod for clamping the fingers in engagement with the collar.

10. In a copy holder, a base, a standard, a copy support hinged with relation to the

standard, said copy support having slots, a sleeve in each slot, a nut threaded on the sleeve, a rod slidable in the sleeve, a spring encircling the rod and having its end bearing against the nut, a nut threaded on the outer end of the rod for confining the outer end of the spring, a collar on the rod near its inner end, fingers on the rod, and a nut on the inner end of the rod for clamping the fingers in engagement with the collar.

11. A copy holding member, sleeves movable with relation to the said member, members slidable in the sleeves, said members being movable at an angle to the surface of the copy supporting member, copy engaging devices on the said members, and means on the slidable members for exerting tension on the copy engaging devices.

12. In a copy holder, a support, sleeves movable with relation to the support, members slidable in the sleeves, copy engaging devices on the said members, and means mounted on the slidable members and engaging the sleeves for exerting tension on the said members.

In testimony whereof, I have affixed my signature in the presence of two witnesses.

GEORGE C. BEIDLER.
